SAFETY RAZOR

Joseph Muros, Newtonville, Mass., assignor to
 Gillette Safety Razor Company, Boston, Mass.,
 a corporation of Delaware

Application October 29, 1949, Serial No. 124,294

10 Claims. (Cl. 30—62)

1

This invention relates to safety razors of the type which employ a thin removable and replaceable blade. In one aspect it comprises a safety razor of new and improved construction that may be manufactured economically by mass production methods, that is convenient in manipulation by the user and accurate and reliable in properly positioning the blade for shaving. The razor moreover is characterized by sound mechanical structure wherein the parts which are movable are guided for free movement without binding and are securely held at rest in operative position during the shaving operation.

Going more into detail, the razor of this invention in its preferred form comprises a stationary guard member having corner lugs, a cap member movable transversely upon the guard member and having a longitudinal blade-locating flange, together with a tongue and slot guiding connection. The blade is engaged and advanced by pressure against its entire rear edge and is guided by connections disposed symmetrically and centrally between the blade-locating lugs of the guard. In this way, free non-binding movement of the cap is insured as well as balanced pressure holding the blade in its shaving position.

These and other features and advantages of the invention will be best understood and appreciated from the following description of a preferred embodiment thereof, selected for purposes of illustration and shown in the accompanying drawings, in which:

Fig. 1 is a view of the razor in side elevation and on an enlarged scale;

Fig. 2 is a fragmentary view in front elevation;

Fig. 3 is a plan view;

Fig. 4 is a fragmentary view in longitudinal section on a still larger scale on line 4—4 of Fig. 2;

Fig. 5 is a fragmentary view in section view on the line 5—5 of Fig. 4;

Figs. 6 and 7 are plan views of the razor head showing certain portions broken away;

Fig. 8 is a view in perspective showing the parts of the razor in exploded relation;

Fig. 9 is a view in perspective showing the guard in inverted position.

In the form herein illustrated the razor is shown as having a handle 10 provided with a reduced threaded tubular end 11 at its upper end. This end is threaded into the pyramidal boss 12 of a rectangular base plate 13. A recess or channel 14 extends longitudinally on the upper face of the base plate and out through one end thereof. This recess provides passage for

2

the pilot of the magazine as will presently be described.

A rectangular guard or blade seat member 15 is secured to the upper face of the base plate 13 and for that purpose is herein shown as provided with countersunk holes for screws 20 although any other securing medium could be employed. The guard member is provided with a longitudinal channel 16 near its front edge 10 which in the complete razor underlies the shaving edge of the blade. At each end of the channel is formed an upstanding lug 17 located in position to engage the opposite ends of the blade edge and position the blade properly for shaving. The forward edge of the guard member is formed as a serrated guard bar 18 and in the rear under face of the guard member is formed a recess or chamber 19 which serves as a transverse guideway for the part 26 to be described below.

Cooperating with the guard member is a cap 22 which is also rectangular in contour and of the same length as the guard member. The cap is provided with a downwardly extending longitudinal flange 23 at its rear edge and with a wide shallow channel 24 in its under face adjacent to the flange 23. The flange 23 is also provided in its outer face with a recess 25 which in the assembled razor is disposed in registration with the chamber 19 of the guard member. The recess 25 is shaped to receive the vertical flange of an angle piece 26 having a horizontal arm shaped to fit as a tongue into the guideway provided by the chamber 19 of the guard member and this arm or tongue is perforated by a longitudinal slot 27 as shown in Figs. 6-8. The angle piece is rigidly secured to the back of the cap by screws shown in Fig. 8 and constitutes in effect a portion of the cap. It constitutes with the chamber 19 of the guard a tongue and groove guiding connection between the cap and guard members of the razor.

A dished rectangular spring plate 28 is shaped to fit the chamber 19 of the guard member and is provided with a square aperture 29 for the passage of a leaf spring 31 carried by a cylindrical plug 30 which is seated in a bore in the upper end of the handle 10. By engaging the horizontal arm of the angle piece 26 the spring plate 28 holds the cap down firmly but yieldingly upon a blade interposed between the cap and guard members of the razor.

The chamber 19 is countersunk to provide a deeper recess 19' for the reception of the upper end of the spring 31 and a shallow wall 19'' ex-

tends across the outer or rear ends of both the chamber 19 and the recess 19'.

As herein shown the razor is adapted to include in its organization a thin flat single-edged blade 32 such as that shown in Fig. 8, although it will be understood that the present invention is not restricted to blades of the specific type shown but by suitable modification it may be adapted for use of blades of other shape, all within the scope of the invention.

From the foregoing description it will be apparent that the angle piece 26 serves to retain the cap 20 in position upon the guard member 15 while permitting it to move transversely thereon. The spring 31 passes upwardly through the slot 27 in the angle piece 26 and through the aperture 29 in the spring plate 28. The spring is bent forwardly so that it tends at all times to move the cap forwardly although it permits rearward displacement of the cap against the spring tension. The spring 31, being flat, is held against twisting by the straight slot 27 of the angle piece and so prevents twisting of the plug 30. The blade 32 rests upon the blade seat of the guard 15 with its unsharpened rear edge in contact with the downwardly extending flange 23 of the cap. Accordingly the yielding forward movement of the cap tends always to advance the blade 22 until the latter is arrested by the engagement of its corners with the lugs 17 which are integral parts of the stationary guard member.

When it is desired to insert a fresh blade in the razor or to remove a used blade, the cap 22 is forced rearwardly against the spring tension so that pressure of the blade against the lugs 17 is released and thus the blade is permitted to be moved upon the surface of the blade seat. Immediately upon the removal of such force the spring blade 31 automatically advances the cap 22 and re-establishes the proper shaving relation of the razor parts.

The cap 22 may be displaced by hand, or as suggested in Figs. 6 and 7, it may be displaced by the pilot 33 of a blade magazine 34. As herein shown the pilot 33 takes the form of a flat blade having a base portion of width to fill recess 14 of base plate 13 and a tapering end shaped to engage the spring blade 31 and force the latter toward the rear of the razor head as the pilot is advanced. When the pilot is fully inserted as shown in Fig. 7 the spring blade 31 together with the cap 22 have been displaced to their extreme rearward position and with them they carry the blade 32 so that its cutting edge is now withdrawn from the lugs 17 as well shown in Fig. 7. The blade may now be ejected under yielding pressure from the outer end of the razor head and immediately replaced by a fresh blade delivered from the magazine 34. It will be noted that the part of the pilot 33 in the recess 14 is entirely below and shielded by a substantial thickness of metal from the blade seat so that it interferes in no way with the endwise movement of the blade.

The parts of the razor as herein shown are designed so that, except the blade and spring parts, they may be readily manufactured as die castings at very moderate expense. It will be seen also that the dished spring 28 is effective to take up any manufacturing variation in the thickness of the cap and to insure adequate frictional grip on the blade under all conditions. Further, the cap and guard members are so related that any substantial twisting is positively prevented at all times and thus there is no danger of bending the tongue of the angle piece

26 which controls the transverse movement of the cap.

Having thus disclosed my invention and described in detail an illustrative embodiment thereof, I claim as new and desire to secure by Letters Patent:

1. A safety razor comprising a base plate having a longitudinal passage therein, a blade-supporting member attached thereto and having blade-locating lugs at one edge and a recess in the other, a cap member slidably engaged with the blade-supporting member, an angle piece fast to said cap member and extending forwardly into the recess in the blade-supporting member, and a spring extending through the passage of the base plate and arranged to bias the cap member toward the lugs of the blade-supporting member.

2. A safety razor of the character described in claim 1 further characterized by a dished spring plate interposed between the said angle piece and the blade-supporting member and being operative to hold the cap member in yielding contact with the blade-supporting member.

3. A safety razor comprising a stationary guard member having blade locating corner lugs, a cap member movable transversely upon the guard member and having a longitudinal blade-locating flange, spring means for moving the cap forwardly in the razor, a spring holding the cap down upon a blade interposed between it and the guard member, and a tongue and groove guiding connection disposed at the center of the cap and guard members and provided by parts of the said members.

4. A safety razor comprising a handle having a longitudinal bore, a blade-supporting member connected to the handle and having blade-locating lugs on its upper face and a recess in its lower face, a cap member transversely movable on the blade-supporting member and having a rigid arm extending into said recess and provided with a slot, a plug in the bore of the handle, and a spring blade carried by the plug, passing through the slot of said arm and acting to urge the cap toward the said lugs.

5. A safety razor comprising cooperating cap and guard members having portions providing a connecting tongue and slot connection permitting relative transverse movement, and spring means pressing on an element of said connection for urging said members into yielding engagement with an interposed blade.

6. A safety razor comprising cooperating cap and guard members, a tongue and slot connection including a tongue projecting from the cap and a guideway in the guard member, a spring acting on said tongue for urging the two members toward each other, and a second spring also acting on the tongue for moving the cap into blade-locating position.

7. A safety razor having cooperating cap and guard members connected for transverse blade-locating movement, the guard having a recess therein, a handle connected to the guard and having a bore therein, and a spring seated in said bore, passing into the recess of the guard and acting to move the cap into blade-locating position thereon.

8. A safety razor having cooperating cap and guard members connected for transverse blade-locating movement, the guard having a recessed guideway in its under face and the cap having a slotted arm movable therein, an apertured spring in said guideway engaging said arm, and a spring blade passing through both the slotted

arm and the apertured spring and acting on the former to cause the cap to position the blade for shaving.

9. A safety razor having inter-connected cap and guard members, a slotted arm being included in the connection between the members, a handle fast to the guard and having a cylindrical bore therein, a plug seated in the bore, and a spring blade carried by the plug and held against twisting by passing through the slot of said arm and acting therethrough relatively to move the cap and guard members.

10. A safety razor having a guard member

with an upper face providing a blade seat and a longitudinal channel in its lower face separated from the blade seat by the body of the guard, a cap member having an extension shaped to underlie said channel, a dished spring located in the channel and yieldingly engaged with the guard and said extension, and an element passing through the spring at substantially right angles in position to be engaged by a magazine pilot inserted into the channel.

JOSEPH MUROS.
